Patented June 12, 1973

227,239

DOUBLE PEDESTAL BUILDING STRUCTURE

Alton D. Wheeler, 3940 Fox Meadow,
Pasadena, Tex. 77502

Filed May 18, 1972, Ser. No. 254,847

Term of patent 14 years

Int. Cl. D25—03

U.S. Cl. D13—1 E

Fig. 1

Fig. 2

Fig. 3

FIG. 1 is a front elevation of the double pedestal building structure; and

FIG. 2 is an end elevation of the building structure of FIG. 1; and

FIG. 3 is a top view of the double pedestal building structure of FIG. 1.

I claim:

The ornamental design for a double pedestal building structure, substantially as shown.
